DESIGN FOR A BROOCH

Harold Weiner, Providence, R. I.

Application July 24, 1937, Serial No. 70,622

Term of patent 3½ years

To all whom it may concern:

Be it known that I, Harold Weiner, a citizen of the United States and residing at Providence, in the county of Providence and State of Rhode Island, have invented a new, original, and ornamental Design for a Brooch, of which the following is a specification, reference being had to the accompanying drawing, forming part thereof, and in which

Fig. 1 is a front elevational view of a brooch showing my new design.

Fig. 2 is a bottom view.

Fig. 3 is an end view.

Fig. 4 is a rear elevational view of the brooch of Fig. 1.

I claim:

The ornamental design for a brooch substantially as shown.

HAROLD WEINER.
